UNITED STATES PATENT OFFICE.

HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

GARMENT-SUPPORTER.

1,290,677.

Specification of Letters Patent.

Patented Jan. 7, 1919.

Application filed June 16, 1914. Serial No. 845,475.

To all whom it may concern:

Be it known that I, HENRY J. STUART, a citizen of the United States, residing at Derby, in the county of New Haven and 5 State of Connecticut, have invented a certain new and useful Improvement in Garment-Supporters, of which the following is a specification.

My invention relates to garment supporters but particularly to the loop-and-button-clasp type, and its object is to provide a button having its base made of resilient and compressible material and slotted to enable the same to be strung by the tab which carries the button. Another object is to provide a button of this character in which all of its parts are integral, thereby eliminating the process of assembling, and a further object is to provide a button base having a 10 gripping surface which can be pressed against the garment by the button loop to facilitate the holding qualities of the button.

I attain these and other objects of my invention by the device set forth in the following description and accompanying drawings in which like reference characters refer to corresponding parts.

In the drawings:

Figure 1 is a front view of the lower extremity of a hose supporter;

Fig. 2, a central longitudinal section thereof;

Fig. 3, a front view of the button, and

Figs. 4, 5, 6 and 7, detail views of modifications.

The loops and button clasp, which is shown loosely mounted on the looped extremity of the supporting strap A, consists of an attaching link B, a button tape or loop C and a button tab D which carries a button E at its lower extremity. The button loop C, which is connected to the lower side of the link B by a sheet metal binding strap F, is provided with a bridge G and has the 10 sides of its lower extremity contracted to engage the shank of the button E. With the exception of the button E the device thus far described is one of the common forms of loop and button clasps well known in 15 the art. The button E consists of a head 2, a shank 3 and a base 4, which latter is provided with a slot 5 and a narrower slot or slit 6. All of the parts of the button are

made integral by molding or otherwise shaping the same out of a yielding or compressible material, preferably rubber or a composition having properties like rubber. The button E is attached to the tab D by bending or flexing the base 4 transversely and forwardly to open the front edges of the slit 6 into which is inserted the end 7 of the tab. The base 4 is then flexed in the opposite direction to open the back edges of the slit so that the end 7 of the tab can be pulled through the slit. The flexed base 4 is then permitted to return to its normal position in which the sides of the slit come together and close, or substantially close, upon the tab extremity 7, thereby pinching or gripping the latter between the walls of the slit. The tab is then carried around the lower extremity of the base 4 in back of the same, then passed forwardly through the slot 5, then along the back of the button loop C and has its upper extremity 75 passed forwardly over the bridge G and around the binding strap and stitched to itself at s, s thereby forming a terminal loop in a manner well known in the art. In this manner the button is fastened to the 80 tab and the tab extremity 7 is securely gripped between the walls of the slit 6. The button being made of yielding material performs all the functions of the so-called rubber buttons which are well known in the 85 art, the advantages of which are particularly set forth in the Gorton Patent No. 552,470, granted December 31, 1895, for an improvement in hose supporters, in addition to the features of the locking slit 90 above described. An equally advantageous feature of my button also resides in the making of the head and shank integral with the slotted base, thereby eliminating the assembling operations usually employed in 95 metal buttons, which latter are often defective due to the fact that the riveted shanks are liable to come loose during the process of finishing.

I may employ one or more slots according 100 to the manner in which it is desired to string the base plates, it being obvious that the multiplication of the slots will increase the grip on the tape. Although the employment of a narrow slot the edges of which 105 are adapted to pinch the tape is one of the

features of my invention yet all of the slots may be wider than the thickness of the tape as shown in Figs. 4 and 5 in which the button E' is provided with a base 7 having 5 slots 8 and 9. In this modification the end 10 of the tab D' is passed rearwardly through the slot 9 and drawn along the under side of the base 7. The tab is then carried around the lower end of the base 7 in 10 back of the tab end 10 and then passed forwardly through the slot 8 so that the frictional surface presented by the faces of the base and the binding action around the edges of the slots and the lower edge of the 15 base causes the base to cling to and firmly grip the tape. In utilizing the so-called rubber buttons heretofore known in the art a fold in the garment embraces the head and shank of the button and is fastened 20 thereto by the contracted portion of the button loop. The garment is prevented, however, from being pressed against the base plate between the slots by reason of the folds of the tape passing over the upper and 25 lower portions of the base. In other words, the contracted portion of the button loop strikes against these folds and can not press the garment against the front face of the base between the slots, a particular instance 30 being shown in Figs. 1 and 2. To overcome this I have raised a portion of the base plate between the slots so that the fold in the garment may be pressed against the same by the button loop and thereby exert a grip 35 on the under side of the garment fold. This elevated gripping surface is shown in Figs. 6 and 7 in which the base plate E' is provided with a raised gripping surface 10 against which the contracted portion of the 40 button loop C presses the fold in the garment. Thus, a greater surface grip is given to the garment fold and thereby distributes the wear thereon and makes the same less liable to be torn apart.

45 While the preferred forms of my invention are embodied in the devices above described yet the invention is susceptible to such modification as may come within the scope of the appended claims.

50 Having now described my invention what

I claim and desire to protect by Letters Patent is:

1. A button for garment supporter clasps comprising a shank and a base, the said base being made out of resilient and compressible material and being slotted adjacent to said shank. 55

2. A button for garment supporter clasps having its base provided with a slit the edges of which are adapted to pinch and grip a supporting tape, the said base being made out of yielding and compressible material. 60

3. A button for button tabs comprising a shank and a slotted base through which a tab is adapted to be passed, the said base 65 and shank being made integral out of resilient and compressible material.

4. A button for a button tab comprising an integral shank and base made out of resilient and compressible material, the said 70 base being independent of the tab.

5. A hose supporter button having a slotted base made out of yielding and compressible material, the said base being provided with an integral raised portion between the 75 slots.

6. A hose supporter button of the kind having its base formed with a slot for the passage of tape characterized by the fact that the slot is provided with an elastic edge 80 for gripping the tape.

7. A hose supporter button of the kind having a slotted base for the passage of tape characterized by the fact that said base is provided with an elastic surface for gripping the tape. 85

8. A hose supporter button of the class which are mounted on tape comprising a base having an elastic portion which presents a clinging surface to tape stretched 90 over said surface.

9. A hose supporter button of the class which are mounted on tape comprising a base having an elastic edge around which tape is adapted to bind to prevent the tape 95 from slipping.

HENRY J. STUART.
